BY

UNITED STATES PATENT OFFICE.

JONAS A. KRETZER, OF MOUND CITY, MISSOURI.

STEAM ASH-REMOVER FOR BOILERS.

No. 868,455.

Specification of Letters Patent.

Patented Oct. 15, 1907.

Application filed March 26, 1907. Serial No. 364,689.

To all whom it may concern:

Be it known that I, JONAS A. KRETZER, a citizen of the United States, residing at Mound City, in the county of Holt and State of Missouri, have invented 5 new and useful Improvements in Steam Ash-Removers for Boilers, of which the following is a specification.

This invention relates to boiler appliances and relates more particularly to a device for removing the ashes from the boiler furnace by means of the injecting action of a jet of steam directed into a suitably arranged conveyer or duct.

The invention has for one of its objects to improve and simplify the construction and operation of apparatus of this character so as to be comparatively easy 15 and inexpensive to manufacture, composed of few parts, easy to manipulate, and thoroughly effective in use.

A further object of the invention is the provision of an ash and cinder collecting means disposed below 20 the boiler grate and provided with an outwardly discharging duct having a deflector at its outer end for discharging the ashes and cinders in any desired direction.

With these objects in view and others, as will appear 25 as the description proceeds, the invention comprises the various novel features of construction and arrangement of parts which will be more fully described hereinafter, and set forth with particularity in the claims appended hereto.

30 In the accompanying drawings, which illustrate one of the embodiments of the invention, Figure 1 is a transverse section of a boiler and of the ash-removing device, the discharge duct of the latter having an intermediate portion broken away: Fig. 2 is a horizontal

35 section on line 2—2, Fig. 1. Fig. 3 is a perspective view of the hood or deflector for directing the ashes and cinders discharged from the duct. Fig. 4 is a transverse section on line 4—4, Fig. 2.

Similar reference characters are employed to designate 40 similar parts throughout the several views.

Referring to the drawing, 1 designates a fire tube boiler of any approved construction having the usual masonry setting 2 and a firebox 3 and ash-pit 4. One of the walls of the setting has an opening 5 through 45 which the discharge duct or pipe 6 of the ash remover extends. Under the grate 7 is a collecting chamber 8 having a hopper 9 whereby the ashes and cinders are directed from the grate to the chamber 8, there being an inclined plate 10 in the chamber which assists in 50 directing the ashes and cinders into the mouth or funnel 11 of the duct 6. Arranged in axial alinement with the duct, which latter may be of any desired length and diameter, is a steam discharging nozzle 12 connected with a pipe 13 extending horizontally through 55 one wall of the boiler setting and through the inclined plate 10. This pipe is connected with the dome 14

of the boiler by a pipe 15 having a hand-controlled valve 16, whereby the supply of steam to the device can be opened or closed and regulated.

By opening the valve 16, a powerful jet of steam is 60 discharged through the duct 6 so that as the ashes and cinders drop through the grate during the cleaning of the fire, they will be sucked through the duct by the steam and discharged therefrom, thus relieving the fireman of the necessity of manually disposing of the 65 ashes.

On the outer end of the duct 6 is arranged a device for directing the stream of ashes and cinders in any desired direction so as to prevent a pile being deposited directly at the end of the duct and interfering with its 70 successful operation. This device comprises a scoop-shaped deflector or hood 17 pivotally mounted at 18 so as to be adjusted to either the dotted or full line position shown in Fig. 2, whereby the ashes and cinders 75 may be deflected to the right or the left. The hood 17 is pivoted on a frame composed of top and bottom members 19 arranged exterior to the duct 6 and pivoted at 20 to a split clamping ring 21 encircling the duct 6. Connected with each member 19 at an intermediate point thereof is a semi-circular strip 22 that serves as 80 a stop adapted to engage the duct and hold the hood in a central position. By pivotally mounting the members 19, the hood can be thrown to one side and out of line with the duct so that the ashes and cinders will discharge in a straight line outwardly from the latter. 85 After a pile has been thus produced, the hood supporting frame can be thrown back to the full line position, Fig. 2, whereby the ashes are thrown laterally to one side or the other according to the adjustment of the hood. 90

From the foregoing description, taken in connection with the accompanying drawings, the advantages of the construction and of the methods of operation will be readily apparent by those skilled in the art to which the invention appertains, and while I have described the principle of operation of the invention, together with the apparatus which I now consider to be the best embodiment thereof, I desire to have it understood that the apparatus shown is merely illustrative and that such changes may be made when desired as are within the scope of the claims. 95 100

Having thus described the invention, what I claim is:—

1. In an apparatus of the class described, the combination of a firebox including a grate, a collecting chamber below the grate, a hopper between the chamber and grate, a duct leading from the chamber, an inclined plate for directing the ashes and cinders into the duct, a steam discharging pipe extending through and supported on the inclined plate and arranged in axial alinement with the duct, and a deflecting device at the outer end of the duct. 105

2. In an apparatus of the class described, the combination of a furnace having an opening in one wall commun- 110

cating with the ash pit, a grate, an inclined plate in the ash pit arranged to direct the ashes from the grate to the opening, a steam discharging pipe passing horizontally through and supported on the wall opposite from that having the opening and arranged with its discharge end extending through the inclined plate and located centrally in line with the opening, a horizontal duct secured in the opening for receiving the ashes ejected by the jet of steam discharged from the pipe, and a deflecting device mounted 5 on the outer end of the duct to be turned thereon and including an adjustable hood for deflecting the material to one side or the other.

3. In an apparatus of the class described, the combination of a furnace, a duct leading from the ash box thereof, 10 means for ejecting the ashes through the duct, and a de-

flecting device on the outer end of the duct, said device comprising a split ring adjustably clamped to the duct, a pair of oppositely disposed bars hingedly connected with the ring, a hood pivotally mounted on the outer ends of the bars, and a member connected with the bars at a point intermediate the ring and hood for engagement with the outside of the duct to hold the deflecting device in proper relation to the duct. 20

In testimony whereof, I affix my signature in presence of two witnesses.

JONAS A. KRETZER.
